CLAIM

I claim the ornamental design for a hang tag hanger, as shown and described.

DESCRIPTION

FIG. 1 is a front view of a hang tag hanger of the present invention;

FIG. 2 is a right side perspective view thereof, in which the tabs used to hang the hang tag are bent toward the front of the hang tag hanger in an alternate position of use;

FIG. 3 is a front view of a hang tag hanger of the present invention, in which it is being used to hang a hang tag;

FIG. 4 is a front view of an alternate embodiment of the hang tag hanger of the present invention;

FIG. 5 is a right side perspective view of the alternate hang tag hanger of the present invention, in which the tabs used to hang the hang tag are bent toward the front of the alternate hang tag hanger in an alternate position of use; and,

FIG. 6 is a front view of the alternate hang tag hanger of the present invention, in which it is being used to hang a hang tag.

The evenly spaced broken lines in FIG. 1 represents a score line, forming no part of the claimed design. The dot-dot-dash broken lines in FIGS. 3 and 5 are for illustrative purposes only and form no part of the claim.
